UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,257,362.

Specification of Letters Patent.

Patented Feb. 26, 1918.

Application filed April 24, 1917. Serial No. 164,171.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

The invention relates to telephone 10 change systems, and more particularly to such systems of the central energy type, its object being to provide improved signaling means for such systems.

In accordance with a feature of this 15 invention, a link circuit having a signaling device and a supervisory relay is provided with a differentially-wound local circuit relay which coöperates with the supervisory relay to cause the intermittent operation of 20 the signaling device, whereby said device furnishes a characteristic signal.

This invention is illustrated in the accompanying drawings; wherein,

Figure 1 shows two ordinary telephone 25 line circuits and a link circuit embodying the present invention;

Fig. 2 shows a link circuit embodying a 30 modification of this invention in which an answering supervisory signaling device is intermittently operated to furnish a recall signal from a connected calling line and a calling supervisory signaling device is intermittently operated to furnish a disconnect signal from either of the connected 35 lines,

Fig. 3 shows two ordinary line circuits and a link circuit embodying another modification of this invention, in which an answering supervisory signaling device is 40 intermittently operated to furnish a recall signal from a connected calling line, and the calling supervisory signaling device is operated continuously to furnish a disconnect signal from either of the connected lines;

Fig. 4 shows a link circuit embodying this 45 invention in which the apparatus is shown in one of its more simple forms;

Fig. 5 shows two ordinary telephone line 50 circuits and a link circuit embodying a still further modification of this invention in which a calling supervisory signaling device is intermittently operated to furnish a recall

signal from the original calling station connected with the link circuit;

Fig. 6 shows a link circuit adapted for 55 operation with the line circuits of Figs. 1, 3 or 5, and in which the line signaling device of a connected line is intermittently operated to furnish a recall signal; and

Fig. 7 shows a link circuit embodying an 60 additional modification of this invention, in which both the answering and calling supervisory signaling devices are intermittently operated to furnish a recall signal from a 65 connected calling line.

In the various figures of the drawings, 70 similar pieces of apparatus will be designated by the same reference character. It is believed that this invention is not of such a character as to require a detailed description of the apparatus appearing in each of the figures and for this reason only a description of the operation will be included.

Figure 1.

Subscriber A having signaled the central office in the usual manner, the operator inserts answering plug 15 into line jack 16, whereupon differentially-wound relay 17 and cut-off relay 18 are operated over a circuit from battery through the upper winding of relay 17, sleeve contacts of plug 15 and jack 16 and the winding of cut-off relay 18 to ground. The energization of the upper winding of relay 17 is sufficient to attract 85 the two upper and the three lower armatures. Answering supervisory relay 19, upon the insertion of the plug in the jack, is also operated. The actuation of relay 17 connects the operator's telephone set to the 90 cord circuit, and the operator, upon being advised that connection is desired with the line of subscriber B, inserts calling plug 25 into line jack 26, whereupon relay 27 and cut-off relay 28 are operated. The operation 95 of relay 27 causes calling supervisory lamp 29 to be lighted, and completes a circuit for the lower winding of relay 17, which may be traced from battery through the lower winding of relay 17, left-hand alternate contact of relay 27, and contact 20 of relay 17 to ground. Since the direction of flow of current through the two windings of relay 17 is opposite, this relay releases its armatures,

In releasing, the normal contacts of the upper armatures of this relay 17 are made before the alternate contacts of the lower armature are broken. Therefore, although 5 contact 20 is opened when relay 17 releases, the circuit including the lower winding thereof is maintained through the normal contact 21 of relay 17, alternate contact of supervisory relay 19, and contact 22 of relay 10 17 to ground. The release of the lower armatures of relay 17 also disconnects the operator's telephone set from the line. Subscriber B may be signaled in any desired manner, and in response to such a signal, 15 moves the receiver from the switchhook, causing the actuation of calling supervisory relay 30, whereupon the calling supervisory lamp 29 is effaced.

Upon the conclusion of the conversation, 20 both subscribers restore the receivers to the switchhooks, causing the release of supervisory relays 19 and 30, the release of the latter causing the lighting of calling supervisory lamp 29. The release of relay 19, 25 when subscriber A restores his receiver to the switchhook, opens the hereinbefore described circuit through the lower winding of relay 17.

Another circuit, however, exists for this 30 lower winding which includes left-hand contact of relay 27 and resistance 31. This resistance 31 serves to unbalance the inductive effect of the two windings of relay 17, whereupon the relay is sufficiently energized 35 to cause the attraction of its upper armatures, the lower armatures remaining in their normal position. The closure of contact 23 of relay 17 completes the circuit for answering supervisory lamp 32, which is 40 now lighted to furnish a disconnect signal.

Should the calling subscriber A desire to 45 initiate another call before the plugs of the cord circuit C are removed from the lines A and B, the removal of the receiver by subscriber A will cause the operation of answering supervisory relay 19, whereupon lamp 32 will be intermittently operated to furnish a recall signal. The circuit over which the lamp is intermittently lighted may be traced 50 from battery through the lamp 32, contact 23 of relay 17, alternate contact of supervisory relay 19, contact 24 of relay 17, contact 33 of relay 27, and interrupter 34 to ground. The operator, observing the 55 flashing of the answering supervisory lamp 32, removes the calling plug 25 from jack 26, whereupon relay 27 releases to efface the calling supervisory lamp 29, and to open the flashing circuit of lamp 32. In addition, the 60 circuit through the lower winding of relay 17 is interrupted at the left-hand contact of relay 27, whereupon relay 17 is sufficiently energized to attract all of its armatures, thereby connecting the operator's telephone 65 set to the cord circuit. The operator may

now converse with subscriber A, and complete in the manner hereinbefore described any connection desired.

Figure 2.

Assuming that the operator, in answering a call from subscriber A, employs the cord circuit of Fig. 2, differentially wound relay 37 thereof and cut-off relay 18 are operated over a circuit from battery through the 75 lower winding of relay 37, sleeve contacts of plug 15 and jack 16, and the winding of cut-off relay 18 to ground. Relay 37, in operating, attracts all of its armatures. Upon the insertion of the plug into the jack of a calling line, answering supervisory relay 19 also operates. Relays 37 and 19 being operated, answering supervisory lamp 32 is intermittently operated over a circuit from battery through the alternate contact of relay 19, 80 contact 38 of relay 37, lamp 32 and interrupter 34 to ground. The operator may now actuate listening key 39 to connect the operator's telephone set to the cord circuit. Upon the operation of this listening key, a 85 circuit through the upper winding of relay 37 is established over a path from battery through contact 40 of listening key 39, and upper winding of relay 37 to ground. Since relay 37 is differentially wound, it now releases its armatures, whereupon a second circuit through the upper winding is established from battery through the alternate contact of relay 19, contact 41 of relay 37 and the upper winding thereof to ground. Relay 37, in releasing its armature, also stops the intermittent operation of answering supervisory lamp 32.

After conversing with the calling subscriber, the operator may restore the listening key to its normal position and complete the connection with the line of a desired party, for example, subscriber B, by the insertion of calling plug 25 into the line jack 26 of the desired line. Relay 42 of the cord 105 circuit and the cut-off relay of the line are thereupon operated. Relay 42 in operating causes the lighting of calling supervisory lamp 45 over a circuit from battery through contact 44 of relay 37, left-hand contact of relay 42, lamp 45, contact 46 of relay 37, normal contact of calling supervisory relay 30, left-hand normal contact of relay 43, and middle contact of relay 42 to ground.

Subscriber B may be signaled in any desired manner. In answering, the removal of the receiver from the switchhook causes the operation of calling supervisory relay 30, whereupon relay 43 is actuated over a circuit from battery through contact 44 of relay 37, left-hand contact of relay 42, calling supervisory lamp 45, contact 46 of relay 37, alternate contact of calling supervisory relay 30, and right-hand normal contact of relay 43 and the winding thereof to ground. 130

Relay 43, in operating, establishes a locking circuit for itself from battery through the right-hand contact of relay 42, right-hand alternate contact of relay 43 and the winding thereof to ground. The operation of calling supervisory relay 30 also extinguishes the calling supervisory lamp 45.

Upon the conclusion of the conversation, the restoration of the receivers to the switchhooks causes the release of supervisory relays 19 and 30. The release of relay 19 opens the hereinbefore traced circuit for the upper winding of relay 37, which now operates, establishing a circuit over which lamp 45 is flashed. This circuit may be traced from battery through normal contact of supervisory relay 19, lamp 45, contact 47 of relay 37 and interrupter 34 to ground. This circuit is under control of the calling subscriber. Should subscriber B have restored the receiver to the switchhook before subscriber A, lamp 45 would be flashed to indicate a disconnect signal, the circuit therefore being from battery through contact 44 of relay 37, left-hand contact of relay 42, lamp 45, contact 46 of relay 37, normal contact of relay 30, left-hand alternate contact of relay 43 and interrupter 34 to ground.

After both receivers have been restored to the switchhooks and before the plugs of the cord circuit are withdrawn from the jacks of the two lines, should subscriber A desire to make a recall, the removal of the receiver from the switchhook by subscriber A would cause the answering supervisory lamp 32 to be flashed to furnish a recall signal to the operator. Upon the removal of the receiver from the switchhook by subscriber A, answering supervisory relay 19 is operated, whereupon a flashing circuit for lamp 32 is completed from battery through alternate contact of answering supervisory relay 19, contact 38 of relay 37, lamp 32 and interrupter 34 to ground. The actuation of the listening key 39 by the operator in answer to the flashing of lamp 32 completes the circuit through the upper winding of relay 37, whereupon this relay releases its armatures and establishes the hereinbefore traced second circuit through the upper winding thereof. The flashing of lamp 32 is thereupon stopped. The operator, upon being advised of the number desired, may withdraw the plug 25 from the jack and insert it in the jack of a desired line. When the plug is withdrawn from the original jack, relays 42 and 43 are released, and when the plug is inserted in the jack of the desired line, relay 42 again operates.

60

Figure 3.

The insertion of calling plug 15 of the cord circuit C into jack 16, in response to a call by subscriber A, causes the operation of differentially wound relay 57. Answer-

ing supervisory relay 19 also operates, thereby causing the flashing of a recall lamp 32 over a circuit from battery through the alternate contact of relay 19, upper alternate contact of relay 57, lamp 32, and interrupter 34 to ground. The actuation of listening key 39 connects the operator's telephone set to the cord circuit, and also completes a circuit through the upper winding of differential relay 57, whereupon this relay releases its armatures, and establishes another circuit through its upper winding from battery through the alternate contact of relay 19, upper normal contact of relay 57 and the upper winding thereof, to ground. Finding that the line desired is that of subscriber B, the operator restores the listening key 39 to normal position and inserts the calling plug 25 into line jack 26, whereupon cut-off relay 28 is actuated. Subscriber B may be signaled in any desired manner, and in responding, causes the operation of calling supervisory relay 30. The operation of relay 30 opens the circuit of the upper winding of differential relay 58, whereupon this relay 90 operates over a circuit including its lower winding.

At the conclusion of the conversation, subscribers A and B restore the receivers to the switchhooks, causing the release of relays 19 and 30. The release of relay 30 causes the lighting of disconnect lamp 59 over a circuit from battery through contact of relay 30, alternate contact of relay 58 and the lamp 59 to ground. The release of relay 19 opens the circuit through the upper winding of relay 57, whereupon this relay operates, closing another circuit through disconnect lamp 59, which may be traced from battery through normal contact of relay 19, lower alternate contact of relay 57 and the lamp 59 to ground.

Before the plugs of the cord circuit C are withdrawn from the jacks of the two lines, should subscriber A desire to initiate another call, the removal of the receiver from the switchhook causes the operation of relay 19, whereupon the recall lamp 32 is intermittently operated over a circuit from battery through the alternate contact of relay 19, upper alternate contact of relay 57, lamp 32 and interrupter 34 to ground. The intermittent operation of this lamp indicates a recall signal to the operator, who may now actuate listening key 39 to connect the operator's telephone set across the cord circuit, and to cause the release of relay 57 in the manner hereinbefore described, which stops the intermittent operation of recall lamp 32. The removal of the plug 25 from the jack 26 by the operator, causes the release of differential relay 58.

Figure 4.

Assuming that the operator in answering 130

the call from subscriber A, employs the cord circuit of Fig. 4, the insertion of the plug 15 thereof into jack 16 causes the operation of cut-off relay 18 in the manner hereinbefore described, and also causes the operation of a differentially-wound relay 67 over a circuit which includes its upper winding. Answering supervisory relay 19 also operates, whereupon answering supervisory lamp 32 is intermittently operated over a circuit from battery through lamp 32, upper alternate contact of differential relay 67, alternate contact of relay 19, lower alternate contact of relay 67 and the interrupter 34 to ground. The operator may actuate listening key 39 to connect the operator's telephone set to the cord circuit, and in so doing, completes a circuit through the lower winding of relay 67 which includes the contact 40 of listening key 39. Relay 67 thereupon releases its armatures, stopping the intermittent operation of lamp 32 and establishing another circuit through its lower winding which may be traced from battery through the lower winding and lower normal contact of relay 67, alternate contact of relay 19 and upper normal contact of relay 67 to ground. The connection with a called line may be completed in the usual manner, after listening key 39 has been restored to normal position. Upon the restoration of the receiver to the switchhook by subscriber A at the conclusion of the conversation, relay 19 releases, opening the hereinbefore traced circuit through the lower winding of relay 67, which now operates, causing the continuous operation of answering supervisory lamp 32 over a circuit from battery through lamp 32, upper alternate contact of relay 67 and normal contact of relay 19 to ground. If, before the operator withdraws the plugs from the jacks, subscriber A desires to initiate another call, the removal of the receiver from the switchhook causes the operation of relay 19, whereupon lamp 32 is intermittently operated over the hereinbefore traced circuit to furnish a recall signal.

Figure 5.

In answering a call from the subscriber on line A, the operator inserts the answering plug of cord circuit C into line jack 16 of line A, whereupon differentially-wound relay 77 operates through its upper winding in series with the cut-off relay 18 which also operates. The answering supervisory relay 19 also operates. Upon the operation of the differentially-wound relay 77, relay 78 operates over a circuit from battery through the winding of relay 78, lower alternate contact of relay 77, and alternate contact of supervisory relay 19 to ground. Upon the operation of relay 78, the calling

supervisory lamp 29 is intermittently operated to furnish a signal. The operator, upon actuating listening key 39, connects the operator's telephone set to the cord circuit, and completes a circuit through the lower winding of the differentially-wound relay 77, which thereupon releases and establishes a second circuit through the lower winding thereof. This second circuit may be traced from battery through the lower winding of relay 77, lower normal contact of relay 77, and alternate contact of supervisory relay 19 to ground. Upon the release of relay 77, relay 78 is released, stopping the intermittent operation of calling supervisory lamp 29. Upon being advised that the line of subscriber B is desired, the operator restores the listening key to normal position and inserts the calling plug 25 into the line jack 26, whereupon relay 79 and cut-off relay 28 are operated. The operation of relay 79 causes the calling supervisory lamp 29 to be lighted over a circuit from battery through the lamp 29, normal contact of relay 78, contact of relay 79 and contact of relay 30. Subscriber B may now be signaled in any desired manner, and in responding, removes the receiver from the switchhook, thereby causing the operation of supervisory relay 30, whereupon the calling supervisory lamp 29 is effaced.

At the conclusion of the conversation, the subscribers restore the receivers to the switchhooks, causing the release of relays 19 and 30. The release of relay 30 causes the lamp 29 to be lighted. Upon the release of answering supervisory relay 19, the circuit through the lower winding of relay 77 is opened, and this relay operates, causing answering supervisory lamp 32 to be lighted. These two lamps now serve as disconnect signals.

Should subscriber A desire to initiate another call, before the plugs are withdrawn from the jacks, the removal of the receiver from the switchhook by subscriber A causes the operation of supervisory relay 19, whereupon relay 78 operates and causes the intermittent operation of a lamp 29, which serves as a recall signal to the operator. In response to this signal, the operator actuates the listening key, which releases relays 77 and 78 in the manner hereinbefore described.

Figure 6.

Assuming that the operator, in answering the call from the subscriber on line A, employs the cord circuit of Fig. 6, differentially-wound relay 87 and answering supervisory relay 19 thereof operate upon the insertion of the answering plug 15 into the line jack 16. The cut-off relay of the line circuit also operates. If the listening key

- 39 is not actuated when relays 87 and 19 operate, relay 88 will be operated over a circuit from battery through the winding of relay 88, lower alternate contact of relay 87 and alternate contact of relay 19 to ground. Relay 88, in operating, connects a coil 89 of low resistance across the tip and ring conductors of the cord circuit, and through the operation of interrupter 34, intermittently connects a resistance 86 in parallel with the winding of the cut-off relay 18. The value of this resistance 86 is such that when it is connected in parallel with the winding of cut-off relay 18, the cut-off relay will release its armatures, whereupon line relay 14 will be operated, causing the line lamp 13 to be lighted. This line lamp will be intermittently lighted to furnish a characteristic signal to the operator. Upon the actuation of the listening key 39, the operator's telephone set is connected to the cord circuit, and a circuit is established for the lower winding of differential relay 87, whereupon this relay releases, establishing another circuit through the lower winding of this relay which includes the lower normal contact thereof and the alternate contact of answering supervisory relay 19. The release of relay 87 causes the release of relay 88, removing the bridge from across the talking strands of the cord circuit, and removes interrupter 34 and resistance 86 from parallel relation with the winding of the cut-off relay 18, thereby stopping the intermittent lighting of line lamp 13. The operator, upon being advised of the number of the called line, restores the listening key to normal position, and completes connection in the usual manner.
- 40 At the conclusion of the conversation, subscriber A, in restoring the receiver to the switchhook, causes the release of relay 19, which opens the circuit through the lower winding of relay 87, permitting this relay to operate, whereupon answering supervisory lamp 32 is operated over a circuit from battery through the lamp 32, upper alternate contact of relay 87 and normal contact of relay 19 to ground. The lighting of this lamp serves as a disconnect signal. If, before the plugs are withdrawn from the jacks, subscriber A desires to initiate another call, the removal of the receiver from the switchhook causes the operation of the answering supervisory relay 19, whereupon relay 88 is operated and cut-off relay 18 is thereafter intermittently released, causing the intermittent lighting of line lamp 13 to furnish a recall signal to the operator. The purpose of resistance 89, which is bridged across the talking strands upon the operation of relay 88, is to provide a low resistance path for line relay 14 to insure the operation of this relay each time that the cut-off relay releases. The operator, in response to the recall signal, may now actuate the listening key and complete the connection with any line desired.

- Figure 7.
- Assuming that the operator, in answering a call from subscriber A, employs cord circuit of Fig. 7, the insertion of the answering plug 15 thereof into line jack 16 causes the operation of differentially-wound relay 97 and cut-off relay 18 over a circuit from battery through answering supervisory lamp 32, right-hand winding of relay 97, sleeve contacts of the answering plug 15 and line jack 16, and the winding of cut-off relay 18 to ground. Answering supervisory relay 19 also operates, whereupon, if the listening key 39 is not actuated, answering supervisory lamp 32 will be intermittently operated, due to resistance 98 being intermittently connected in parallel with the lamp as a result of the rotation of interrupter 34. When the listening key is actuated, the operator's telephone set is connected with the cord circuit, and the circuit of the left-hand winding of differential relay 97 is completed, whereupon the relay releases. The circuit including the left-hand winding of relay 97 may be traced from battery through the left-hand winding of relay 97, contact 40 of the listening key 39, contact of supervisory relay 19, right-hand winding of the relay 97, sleeve contacts of the answering plug 15 and line jack 16 and the winding of cut-off relay 18 to ground. Upon the release of relay 97, the left-hand normal contact thereof is closed, thereby establishing a locking circuit including the two windings of relay 97 in series opposing. The left-hand winding of relay 97 is now connected in parallel with answering supervisory lamp 32, thereby effacing the lamp.
- The operator, upon being advised of the number of the line with which connection is desired, restores the listening key to normal position and inserts the calling plug 25 into the line jack of the desired line, for example, line jack 26, whereupon calling supervisory lamp 29 is lighted and cut-off relay 28 operated. Subscriber B may be signaled in the usual manner, and, in responding, removes the receiver from the switchhook and causes the operation of supervisory relay 30. This relay in operating connects a shunt circuit, including the resistance 99, about the lamp 29, thereby effacing the lamp.
- At the conclusion of the conversation, subscribers A and B restore the receivers to the switchhooks, whereupon relays 19 and 30 release. The release of relay 19 opens the circuit which includes the left-hand winding of relay 97, whereupon this relay is ac-

tuated and the answering supervisory lamp 32 is lighted to furnish a disconnect signal. If, before the plugs are removed from the line jacks, subscriber A initiates another 5 call, answering supervisory relay 19 is thereby operated, connecting resistance 98 and interrupter 34 in parallel with lamp 32 and resistance 99 and interrupter 34 in parallel with lamp 29, whereupon these two 10 lamps are intermittently operated to furnish a recall signal to the operator. The operator, in response to this signal, may actuate the listening key, whereupon differential relay 97 releases, stopping the intermittent 15 operation of the two lamps.

In each of the cord circuits shown in the various figures, there is a differentially-wound relay included in the answering sleeve strand. Those differential relays 37 20 of Fig. 2, 57 of Fig. 3, 67 of Fig. 4, 77 of Fig. 5, and 87 of Fig. 6, function in very much the same manner, practically the only difference between these relays being in the number of contacts controlled thereby. The 25 differential relay 17 of Fig. 1 also functions like those of the figures mentioned in the preceding sentence, but it has the additional function of controlling the connection of the operator's telephone set to the cord circuit, and is so constructed as to attract only 30 a portion of its armatures when it is only partially energized, as when the circuits including both windings are completed, the resistance 31 being in circuit with the lower 35 winding thereof. The differential relay 97 of Fig. 7 differs from those differential relays of the other figures principally in that the two windings thereof are connected in series opposing in the same circuit rather 40 than in multiple circuits.

From the descriptions of the various circuits shown in the drawings, it will be evident that applicant has provided a system in which a very small amount of apparatus is 45 required to cause the intermittent operation of a signaling device to furnish a recall signal to the operator.

What is claimed is:

1. A telephone exchange system comprising 50 telephone lines terminating at a central office, a link circuit thereat connected with one of the lines, a signaling device in the link circuit, a supervisory relay for the link circuit, an interrupter, and a differentially-wound relay in the link circuit when energized coöperating with the supervisory relay when energized to connect the interrupter in circuit with the signaling device.

2. A telephone exchange system comprising 60 telephone lines terminating at a central office, a link circuit thereat, a listening key, a supervisory relay, a differential relay operating upon connection of the link circuit with one of the lines and releasing upon the 65 actuation of the listening key, a signaling

device, and interrupter mechanism brought into circuit therewith upon the subsequent operation of the differential relay followed by the operation of the supervisory relay.

3. A telephone exchange system comprising 70 telephone lines, a link circuit, a relay having an operating winding and a neutralizing winding, a circuit including the operating winding of the relay completed upon connection of the link circuit with one 75 of the telephone lines, a supervisory relay for the link circuit, an operator's telephone set, a circuit including the neutralizing winding completed when the operator's telephone set is connected with the link circuit, a signaling device, interrupter mechanism, and a circuit for the signaling device and the interrupter mechanism including contacts of both relays.

4. A telephone exchange system comprising 85 telephone lines, a link circuit, a relay having an operating winding and a neutralizing winding, a circuit including the operating winding of the relay completed upon connection of the link circuit with one of 90 the telephone lines, a supervisory relay for the link circuit, an operator's telephone set, a circuit including the neutralizing winding completed when the operator's telephone set is connected with the link circuit, a signaling device, interrupter mechanism, and a circuit including the signaling device and the interrupter mechanism established upon 95 the subsequent operation of the first mentioned relay followed by the operation of the 100 supervisory relay.

5. A telephone exchange system comprising 105 telephone lines, a link circuit, a primary relay having an operating and a neutralizing winding, a circuit including the operating winding completed upon connection of the link circuit with one of the lines, a supervisory relay for the link circuit, a listening key, a circuit including the neutralizing winding completed upon the actuation of the 110 listening key, a signaling device, interrupter mechanism, and a circuit for the signaling device and the interrupter mechanism including contacts of both the primary and the supervisory relays.

6. A telephone exchange system comprising 115 telephone lines, a link circuit, a primary relay having an operating and a neutralizing winding, a circuit including the operating winding completed upon connection of the 120 link circuit with one of the lines, a supervisory relay for the link circuit, a listening key, a circuit including the neutralizing winding completed upon the actuation of the listening key, a signaling device, interrupter mechanism, and a circuit for the signaling device and the interrupter mechanism established upon 125 the subsequent operation of the primary relay followed by the operation of the supervisory relay.

7. A telephone exchange system comprising telephone lines, a link circuit, a primary relay having an operating and a neutralizing winding, a circuit including the operating winding completed upon connection of the link circuit with one of the lines, a supervisory relay for the link circuit, a listening key, a circuit including the neutralizing winding completed upon the actuation of the listening key, a signaling device and interrupter mechanism, and a circuit therefor open at two points, closed at one point upon the operation of the primary relay when the supervisory relay is deenergized and at the other point by the subsequent energization of the supervisory relay.
8. A telephone exchange system comprising telephone lines, a link circuit, a primary relay having an operating and a neutralizing winding, a circuit including the operating winding completed upon connection of the link circuit with one of the lines, a supervisory relay for the link circuit, a listening key, a circuit including the neutralizing winding completed upon the actuation of the listening key, a signaling device and interrupter mechanism, and a circuit therefor open at two points, closed at one point upon the operation of the primary relay when the supervisory relay is deenergized and at the other point by the subsequent energization of the supervisory relay.

In witness whereof, I hereunto subscribe my name this 20th day of April, A. D. 1917.

CHARLES W. KECKLER.
